UNITED STATES PATENT OFFICE

EDWIN E. DARRAGH, OF NEW YORK, N. Y.

DISPLAY BOX

Application filed March 25, 1927. Serial No. 178,170.

This invention relates to display boxes of that class in which the box, in order to advertise its contents, is provided with an advertising or display card which is turned upwards into an erect position at one end of the box. The object of the invention is to provide a novel means for holding the display card erect or in display position which shall be simple, cheap, efficient, and not detract from the appearance of the box.

For a full understanding of the invention, constructions embodying the invention in preferred forms will now be described in detail in connection with the accompanying drawings, and the features forming the invention then be specifically pointed out in the claims.

In the drawings,—

Figure 1 is a perspective view of a box embodying the invention in a preferred form 20 with the display card broken away;

Figure 2 is a detail section on line 2—2 of Fig. 1 with part of the box body broken away;

Figure 3 is a plan view of the display card blank of Figures 1 and 2;

Figure 4 is a perspective of a modified construction with parts broken away, and

Figure 5 is a plan view of the combined display card and easel blank shown in Fig. 4.

Referring now to the drawings, and particularly to Figures 1 to 3, the display card A shown at one end of the box body B may be secured thereto in any desired manner or, as is preferable, may form a part of the blank 35 of the box body B, as clearly shown in Fig. 3. The box body B is shown as supported with one end raised and supported by an easel C which, in the form shown in Figs 1 to 3, is preferably a separate blank secured to the box body B by a tab 1, as in Figures 10 and 11 of my Letters Patent No. 1,505,545.

In accordance with the present invention, the display card A is held erect by lateral pressure on the display card. For this purpose, the lower end of the display card, which is mounted within the box body, is made wider than the box body so that the side panels of the box body coacting therewith squeeze the display card laterally. In the 50 construction shown in Figs. 1 to 3, the lower

portion of the display card blank fits within the box, and is slit centrally to provide a free portion a, which is wider than the inside of the box. The pressure of the side of the box body upon the portion a tends to 55 bulge the display card or portion a and produces a toggle-like action upon the center of the display card A as the latter is bent upward and backward on the line 2 into display position, and as it is folded downward 60 on the same line, so as to hold the card erect in display position and flat in closed position.

In the construction shown in Figs. 4 and 5, the display card A and the easel are formed in a single blank, as shown in Figures 1 to 65 3 of my Letters Patent No. 1,505,545, with the side wings b, c, folded in and interlocked on the base d to form the easel, and secured to the box between the end layers with tab e resting on the top of the box. In this construction the display card A is provided preferably with two cut-out portions f extending beyond the outside edges thereof so as to be put under lateral pressure by the sides of the box, and thus produce the toggle-like 70 action of the construction of Figures 1 to 3, on each side of the display card, to hold the same erect in display position and flat when folded down.

It will be understood that the invention is 80 not limited to combination with an easel for raising the box end, although it is preferably thus used. The form of easel shown, also, is only for purpose of illustration of the invention and any other suitable support for 85 raising the box end may be used.

The invention, moreover, is not to be limited to the specific forms shown and described for securing the lateral pressure on the display card, as many modifications may 90 be made within the invention as defined by the claims.

What I claim is:

1. The combination with a box, of a display card having its lower portion extending 95 into the box and edgewise between the walls of the box, and its upper portion constructed to be bent down within the box when closed and bent upward into erect position above the box for display, the lower portion of said 100

- display card within the box being wider than the box body and edgewise under lateral pressure by the box walls, whereby the display card is held erect when bent into display position.
5. 2. The combination with a box, of a display card having its lower end extending into the box and formed to provide two or more sections laterally of the display card, said sectioned portion of the display card being of such width as to be held under lateral pressure applied on the side edges thereof by the box walls to hold the display card erect when bent into display position.
10. 3. The combination with a box, of a display card having its lower end extending into the box and scored so that the display portion may be bent down within the box when closed and formed to provide two or more sections laterally of its lower end, said sectioned portion of the display card being of such width as to be held under lateral pressure applied on the side edges thereof by the box walls to hold the display card erect when bent into display position.
15. 4. The combination with a box, of a display card having its lower end extending into the box and scored so that the display portion may be bent down within the box when closed and formed to provide two sections laterally of its lower end, said sectioned portion of the display card being of such width as to be held under lateral pressure applied on the side edges thereof by the box walls to hold the display card erect when bent into display position.
20. 5. A display card device, comprising a normally flat display card of flexible material and a distortable support to which one edge of the display card is hingedly connected, said support having two portions displaceable toward each other and adapted to be maintained in displaced positions transmitting forces to the display card through the hinge connection, whereby said card is flexed or distorted out of a true plane for the purpose set forth.
25. 6. A display card device for use with merchandise display boxes comprising a flexible blank having two portions hingedly connected together, one portion comprising a display card and the second portion comprising a support therefor, the support flaring outwardly edgewise away from the hinge line and being slotted intermediate its lateral edges along a line substantially at right angles to the hinge line.
30. 7. A display card device for use with merchandise display boxes, comprising a flexible blank having a display portion and a supporting portion hinged connectedly together, the base of the supporting portion being greater in dimension than the measurement along the hinge line, the purpose being to produce a distortion in the body of the show card for the

purposes set forth by squeezing the supporting portion until the length of the base of the supporting portion is equal to or approximately the length of the hinge line, the base being slotted from the edge thereof to the hinge line to allow the portions of the contracted base to overlap.

70. 8. A display card device for use with merchandise display boxes, comprising a flexible blank having two portions hingedly connected together, one of said portions being slotted, the slot extending from one edge approximately to the hinge, substantially dividing said slotted portion into two parts, and permitting said parts to be moved toward each other to buckle the unslotted portion.

75. 9. A display card device for use with merchandise display boxes, comprising a flexible blank having two portions hingedly connected together, one of said portions being slotted, the slot extending from one edge approximately to the mid point of the hinge, substantially dividing said slotted portion into two approximately equal parts, and permitting said parts to be displaced toward each other to buckle the unslotted portion.

80. 10. A display card device for use with merchandise display boxes, comprising a flexible blank having two portions hingedly connected together, one of said portions being slotted, the slot extending from one edge to an intermediate point of the hinge and perpendicular to the hinge line, dividing the slotted portion into two displaceable parts, and permitting said parts to be displaced toward each other to buckle the unslotted portion.

85. 11. A display card device comprising a flexible display card and a deformable supporting portion hingedly connected together, one of said portions being slotted, substantially dividing said portion into two parts movable toward each other by distorting the other portion, said parts being displaced toward each other, whereby said slotted portion is contracted in a direction parallel to the hinge line, for the purpose set forth.

90. 12. The combination with a box, of a display card device having a display card portion and a support portion hingedly connected together, the support or lower portion of the display card having two displaceable parts rendering it distortable by pressure on its opposite vertical edges, causing the display card to assume an oblique angle relatively to the support as the result of such distortion.

95. In testimony whereof, I have hereunto set my hand.

EDWIN E. DARRAGH.
